UNITED STATES PATENT OFFICE.

EDWARD W. EDWARDS, OF CINCINNATI, OHIO.

DAY AND NIGHT CORNER-SIGN.

SPECIFICATION forming part of Letters Patent No. 715,769, dated December 16, 1902.

Application filed May 19, 1902. Serial No. 107,965. (No model.)

To all whom it may concern:

Be it known that I, EDWARD W. EDWARDS, a citizen of the United States, residing in the city of Cincinnati, in the county of Hamilton 5 and State of Ohio, have invented a certain new and useful Day and Night Corner-Sign; and I do declare the following to be a clear, full, and exact description thereof, attention being called to the accompanying drawings, 10 with the reference-numerals marked thereon, which form also a part of this specification.

This invention relates to signs for advertising purposes, and is arranged and constructed with two purposes in view. One is 15 to render the sign observable and conspicuous in day-time as well as at night. The other is to permit its attachment to a limited projecting surface—as, for instance, at a corner of a building, a column, or post. Accordingly 20 the invention comprises two leading features, one of which is the possibility to be readily observed in daylight as well as at night. The other is the provision for attachment in the manner stated.

25 The invention consists of the construction whereby these features are embodied in practical shape and as hereinafter described, claimed, and illustrated.

In the accompanying drawings, Figure 1 is 30 a front view of the sign in its preferred form. Fig. 2 is a rear view of the same. Fig. 3 is a central horizontal section of it, with adjacent parts of a corner, to which it is attached. Fig. 4 is a side view of it with parts broken 35 away. Fig. 5 is a front view, and Fig. 6 is a top view, show at reduced scale a modified shape of my sign.

The principal means whereby the sign is rendered also observable at night consist of 40 a suitable light inclosed in a chamber, one of the walls of which constitutes the sign proper and is so constructed that the matter on it may be seen in day-time as well as at night, the latter effect being due to the light behind 45 it and within the chamber. This latter may be circular, as shown in Figs. 1 to 4, or rectangular, as shown in Fig. 5. The material of its walls is sheet metal, 10 indicating the rear wall, 11 the side, and 12 the front 50 wall, all connected to each other in any suitable manner. The front wall also constitutes the sign, and as to it consists of two parts—a

center field 13, which may be used to carry a suitable picture, emblem, or trade-mark, as indicated by the star 14 shown, and of a 55 space 12^a surrounding this center part and which may carry the name of a firm or advertising matter, as shown at 15. Around the outer edge of this front wall an ornamental border 16 is provided, which is to be 60 pressed out of the metal and may be scroll-work or an echinus or ovolو molding, as shown in Fig. 1, or a bead, as shown in Fig. 5. Any space not occupied by reading-matter on this annular field 12^a may be filled in by additional ornamental work also pressed out of the metal, as shown at 17. The characters or letters of the matter in space 12^a are produced by rows of perforations closely alined, as shown at 15, and may therefore be readily 65 seen in daylight. For matter on the center field colors are to be used, which matter therefore becomes equally prominent. By reason of the perforations out of which the characters 15 are formed it is clear that the matter 70 may also be readily seen at night as soon as a light is placed within the sign-chamber. By preference I use an electric light, as shown at 18, current to be supplied from any available source or regular service. Other 75 means of illumination may of course be used—as, for instance, a suitable lamp—in which case necessary openings would be provided in the side of the light-chamber to provide for admission of air and ventilation. The 80 light within the chamber is reflected all over by the bright inside of its sheet-metal walls. It is evenly diffused all over the perforations in wall 12 by placing behind them glass 19, which is merely translucent, like, for instance, milk-white or ground glass. This 85 glass is held in position by cleats 21.

In order to render the matter on the center field 13 visible at night, said field is made of glass and held in place around the inner 90 edge of wall 12, which edge is depressed, forming a recess 22, occupied by the edge of the glass. It is held in place by a suitable ornamental molding 23, similar to molding 16 at the outer edge, said molding with its outer 95 edge being attached—by solder, preferably—to wall 12, so as to project with its inner edge over the edge of the glass, thus holding this latter. This glass should be prepared simi-

lar to what has been described as being behind the perforated letters 15—that is, it should be such as to prevent direct passage of the light without first evenly diffusing the same all over this field. This effect may be obtained by using ground or colored glass or by using paint on the same. The trade-mark or other matter 14 is also imparted by the use of colors and painted on the glass in a manner that the matter clearly appears in its natural colors either in day-time or at night with the light behind the same. This matter 14 may also be imparted by using so-called "transfer-pictures" or "transfer-ornaments," which readily appear in their natural colors behind the glass in day-time and become also visible at night with the light behind.

For the purpose of permitting access to the interior of the sign-chamber and to the light therein a door 24 is provided in rear wall 10, hinged at 25 and provided with a suitable catch 26 to keep it closed.

To permit attachment of the sign in the places stated—that is, at a projecting corner 25 of a building, post, column, &c.—and to hold the same firmly in position in such place, there is a recess 27 provided and disposed vertically through the center of the rear wall 10, the internal angle of this recess being fitted 30 to correspond to the angle of the corner 28 of the building or post to which the sign is to be attached. The final connection is made by suitable lugs 29 and nails or screws.

In Fig. 5 the sign is modified to the extent of its shape, which is rectangular. In Fig. 6 35 the recess is shown curved to accommodate a round corner or post. The face or front is also shown convex.

Having described my invention, I claim as new—

In a day and night corner-sign, the combination of a sign-chamber adapted to contain a light and formed between parallel front and rear walls, and the rear wall having an outwardly-open, vertical recess and a door to 45 one side of said recess to permit access to the interior of the chamber, the front wall constituting the sign proper and consisting of a center field of translucent glass, carrying figures applied in colors, a marginal outer field 50 surrounding this center field and having perforations forming sign characters, the inner edge of said outer field being depressed to form a recess 22 to receive the edge of the center field, a molding 23 attached to this outer 55 field so as to project partly over the edge of the center field while the same occupies recess 22, translucent sheets of glass behind said perforations and cleats 21 to hold said sheets in place.

In testimony whereof I hereunto set my hand in the presence of two witnesses.

EDWARD W. EDWARDS.

Witnesses:

C. SPENGEL,
ARTHUR KLINE.
